US00D739200S

(12) **United States Design Patent**
Elder et al.

(10) **Patent No.:** **US D739,200 S**
(45) **Date of Patent:** **** Sep. 22, 2015**

(54) **SCREWDRIVER**

(71) Applicant: **Black & Decker Inc.**, Newark, DE (US)

(72) Inventors: **Christian V. Elder**, Baltimore, MD (US); **Daniel N. Lopano**, Bel Air, MD (US); **Christopher G. Donze**, Towson, MD (US)

(73) Assignee: **BLACK & DECKER INC.**, Newark, DE (US)

(**) Term: **14 Years**

(21) Appl. No.: **29/517,551**

(22) Filed: **Feb. 13, 2015**

3,019,673 A 2/1962 Sjostrand et al.
3,114,423 A 12/1963 Naslund
3,203,490 A 8/1965 McCarty et al.
3,456,740 A 7/1969 Paule et al.

(57) **CLAIM**

The ornamental design for a screwdriver, as shown and described.

DESCRIPTION

FIG. 1 is a perspective view of a screwdriver; FIG. 2 is a front view of the screwdriver of FIG. 1; FIG. 3 is a rear view of the screwdriver of FIG. 1; FIG. 4 is a right view of the screwdriver of FIG. 1; FIG. 5 is a left view of the screwdriver of FIG. 1; FIG. 6 is a top view of the screwdriver of FIG. 1; and, FIG. 7 is a bottom view of the screwdriver of FIG. 1. The broken lines illustrate portions of the screwdriver that form no part of the claimed design.

1 Claim, 6 Drawing Sheets

US D739,200 S
